CONNECTOR WITH WASHER CAP

Marvin Lee, Rye, and Julian Rogoff, New York,
N. Y., assignors to Burndy Engineering Co. Inc.,
a corporation of New York

Application June 16, 1937, Serial No. 148,491

4 Claims. (Cl. 173—269)

This invention relates to connectors and more particularly to connectors employing caps or pressure transmitting elements between nut and cable.

5 In Patent No. 2,049,409 issued to Bern Dibner, a cap of this nature is disclosed. These caps are either cast or forged. When such a cap is clamped on soft drawn copper cable, it is necessary to provide some means of locking the joint 10 against loosening from vibration. This is usually done by using a lockwasher which is inserted between the nut and the cap.

This fourth element added to the cost, and further made it necessary for the installer to 15 take into consideration an additional piece to handle, which would be burdensome in inconvenient locations, waste time, and increase the possibility of parts dropping.

Accordingly, a primary object of our invention consists in providing a cap that possesses 20 all the features of a lockwasher in a single unitary construction, thus eliminating an extra element.

We have found that when soft drawn cables are 25 clamped in these solderless electrical connectors, they have a tendency to be gradually relieved of the clamping pressure for several reasons.

One reason is that the strands of the cable, being clamped under high pressure, will gradually 30 distort and mesh into closer relationship with a resultant smaller diameter.

Another cause is the expansion and contraction of the cable and connector because of temperature changes. If there is any difference at 35 all in the thermal coefficients of expansion of the cable and the connector, a change in temperature will cause an uneven expansion or contraction. A cycle of expansion and contraction may cause the cable to loosen.

40 A third reason is the creep of the cable, which, being preferably of copper possessing a high conductivity, is soft and does not have a yield point. The constant tension or pressure will permanently deform the cable, loosening the 45 connection, and reducing its electrical efficiency.

Another object, therefore, is to provide a cap capable of maintaining a constant pressure on the cable to a degree unobtainable by an ordinary cap and lockwasher.

50 In addition, these caps or pressure transmitting elements had broad pressure applying surfaces, so that the cable would not be deeply indented by point contacts with great pressure concentrations.

All these features necessitated the use of a

solidly forged or cast connector possessing considerable weight, increasing the shipping charges, and adding to the cost of the connector.

A further object, therefore, is to provide a cap, weighing a fraction of the average cap, yet possessing sufficient strength to enable the use of high pressures to insure good electrical joint efficiency and containing sufficiently large pressure areas to avoid point contacts with the cable.

We attain these and other objects, and accomplish our results by providing a sheet metal combined pressure cap and washer, as will be readily apparent from a consideration of the following description and claims taken together with the accompanying drawing in which:

Fig. 1 is a side view of a connector provided with washer cap.

Fig. 2 is an end view of the same.

Fig. 3 is a top view.

Fig. 4 is a top view of the cap.

20

Fig. 5 is a side view of the same.

Fig. 6 is a front view.

Fig. 7 is a side view of our cap applied to another type of connector.

Fig. 8 is a sectional view through the line 8—8 of Fig. 4.

Fig. 9 illustrates the cap with outwardly extending arms.

Referring more particularly to Fig. 1, reference numeral 10 designates the complete connector in 30 which a cable 11 is provided with a terminal block 12.

The connector is provided with main and auxiliary clamping members 13 and 14, with troughs 15 and 16 forming a socket in members 13 and 35 14 respectively.

The cable 11 passes through the eye 17, of the eyebolt 18, which is integral with the main socket member and rises normally thereof, terminating in the threaded bolt section 19. A nut 20 threadedly engages the bolt 19 for applying pressure 40 to the cable.

The auxiliary socket member 14 is in the form of a sheet metal cap having an aperture 21 centrally located on the upper surface 22.

45

The sheet metal cap is preferably drawn into a rectangular cup shaped section with two opposite arms 23 and 24 extending beyond the sides 25 and 26 and inwardly drawn or outwardly, see Fig. 9) and formed into a trough 16, previously 50 described.

While the cap illustrated is rectangular in form, the particular shape is immaterial, the necessary feature residing in a contact surface for the nut, and two normally extending trough 55

shaped arms for receiving the cylindrically shaped cable.

The trough shaped arms 23 and 24 extend inwardly approximately to the sides of the eyebolt 18 and the extreme edges 27 and 28 are downwardly positioned so that they will first engage the cable before the surface of the trough comes in contact with the surface of the cable.

The entire cap 14, is made of springy metal, 10 the two arms 23 and 24, resiliently giving under the applied pressure until there is a surface contact of trough and cable.

The spring effect of the cap may be increased or decreased by raising or lowering the two other 15 side walls, the lowering of these walls reducing the length of the sides 25 and 26 to which the trough arms are attached. This will make the trough arms more rigid and tend to prevent their 20 springing action. Thus when the other side walls have been removed, the sections 25 and 26 remaining provide maximum resiliency to the arms.

The eyebolt 18 may be constructed free of the 25 terminal block 12, and made into an auxiliary socket member, as shown in Fig. 7; the pressure block becomes the current carrying member and its design may be modified accordingly. The 30 terminal block 29 shown in this figure is inserted between the cap and nut, the eyebolt 30, entering an aperture 31 in the extension 32 of the terminal block 29, and the nut tightened as before.

When identical connectors, one with the sheet 35 metal cap and one with the solid forged cap are tightened with identical values of wrench torque, there is an increase in the pull-out value of the sheet metal cap over the forged cap of between 20 to 50%. We attribute this increase in pull-out value to the effect of the edges 27 and 28 40 biting in the cable before the pressure areas engage, holding the cable securely in place.

We have thus described our invention, but 45 we desire it understood that it is not confined to the particular forms or uses shown and described, the same being merely illustrative, and that the invention may be carried out in other ways without departing from the spirit of our invention, such as the use of a washer cap employing our invention in a connector joining two cables together, instead of the terminal shown and, therefore, we claim broadly the right to employ all 50 equivalent instrumentalities coming within the scope of the appended claims, and by means of which, objects of our invention are attained and new results accomplished, as it is obvious that 55 the particular embodiments herein shown and described are only some of the many that can be employed to attain these objects and accomplish these results.

60 What we claim and desire to secure by Letters Patent, is as follows:

1. A connector for electric cables comprising a plurality of cable clamping members forming a socket for receiving a cable, one of which is made of sheet metal having a surface upon which the clamping pressure is applied, and integral therewith, a pair of sections extending transversely to said surface, each terminating in a resilient arm having a cable clamping section extending longitudinally of the cable receiving socket, and means for applying pressure to the surface of the sheet metal cable clamping member for clamping the cable between the members. 5

10 2. A connector for electric cables comprising a plurality of cable clamping members forming a socket for receiving a cable, one of which is made of sheet metal having a surface upon which the clamping pressure is applied, side walls extending transversely to said surface and terminating in a pair of oppositely positioned resilient arms having cable clamping sections extending longitudinally of the cable receiving socket, and means for applying pressure to the surface of the sheet metal cable engaging member for clamping the cable between the members. 15

20 3. A connector for electric cables comprising a plurality of cable clamping members forming a socket for receiving a cable, one of said cable clamping members having extending threaded means, the other of which is made of sheet metal having an apertured surface upon which the clamping pressure is applied, side walls extending transversely to said surface and terminating in a pair of oppositely positioned resilient arms having cable clamping sections extending longitudinally of the cable receiving socket, and a nut 30 for engaging the threaded means projecting through the apertured sheet metal surface for applying pressure thereto and clamping the cable between the members. 35

4. A connector for electric cables comprising a plurality of cable clamping members forming a socket for receiving a cable, one of said cable clamping members having extending threaded means, the other of which is made of sheet metal having an apertured surface upon which the clamping pressure is applied, side walls extending transversely to said surface and terminating in a pair of oppositely positioned resilient arms having cable clamping sections extending longitudinally of the cable receiving socket, a nut for 45 engaging the threaded means projecting through the apertured sheet metal surface for applying pressure thereto and clamping the cable between the members, and a terminal plate for insertion between the nut and one of the cable clamping members, having a plurality of apertures, one for receiving the threaded means and the other for fixedly attaching said connector. 50
